VENEER BEND

Elmo E. Alexander, New Albany, Ind.

Application February 20, 1939, Serial No. 257,450

5 Claims. (Cl. 20—92)

This application is a continuation in part of my United States application Serial Number 202,651, filed April 18, 1938.

This invention relates to the formation of 5 bends in wood and particularly in built-up or ply wood of that nature having a core over which one or more plies of veneer are secured.

The primary purpose of this invention is to provide a structure permitting the formation of 10 a bend in such material which will give a perfectly smooth and continuously curved exterior surface and at the same time may be formed without the necessity of having to insert sticks or the like to complete the inner portion of the bend.

15 A further object of the invention is to provide an exceedingly simple and relatively cheap means for relieving the backside of that zone which is to be bent in a manner which will permit the formation of a smooth interior surface around the 20 bend.

These and many other objects and advantages will become apparent to those versed in the art in the following description of the invention as illustrated in the accompanying drawing, in which 25

Fig. 1 is an inside elevation of a length of a panel in flat form;

Fig. 2, an edge view of the panel;

Fig. 3, a similar edge view but showing the panel in the bent position;

30 Fig. 4, an outside elevation of the bend;

Fig. 5, an edge view of a panel in slightly modified form; and

Fig. 6, an edge view of the panel as indicated in Fig. 2 in a disassembled relation.

35 Like characters of reference indicate like parts throughout the several views in the drawing.

A panel is formed in the usual manner to have a body or core 10 on the outside of which is glued one or more plies of veneer wood 11, herein shown 40 as two in number. The inside of the panel is preferably provided with one or more plies of veneer glued to the core 10, these plies being designated by the numeral 12 and shown as being two in number. The panel is formed flat and

45 the core 10 is cut away from the backside and a ply of veneer 13 is glued directly against the outer plies 11. On top of this added ply 13 is placed a second ply of veneer 14. The ends only of this second ply 14 are glued to the ply 13. Then on 50 top of the ply 14 is placed a block 15 to fill out the balance of the thickness of the core 10 and this block is glued over its entire underside to the ply 14. Over the block 15, and preferably extending somewhat therebeyond, are placed one or

55 more plies of veneer 16 to complete the building

up of this bend zone to the thickness of the balance of the panel.

The outer plies 16 have their grain turned to be transversely directed across the panel rather than longitudinally thereof. Then a number of 5 spaced apart cuts 17 in the nature of slots are made through the plies 16 and through the block 15 down to the ply of veneer 14. The shape of these cuts 17 may vary, but, in the form shown, are narrow V-slots of such width and in such 10 number that when the bend is made these slots will be completely closed and glue placed therein to cause one side of each slot to be held in close 15 intimate contact with the other side. A further cut 18 is made at one end of the block 15 by cutting entirely through the plies 16, the block 15, and the ply 14. This cut is made sufficiently wide, as indicated in Fig. 2, as will permit the rolling up of the block 15 as indicated by the dash lines, it being remembered that this top ply 14 is 20 not glued to the under ply 13 throughout its major length.

The panel is then bent to give the desired curve, here shown as a ninety degree curve, Fig. 3, whereupon the block 15 will be carried around, as 25 indicated, to close the slots therein and to cause the end cut to be completely closed by relative longitudinal travel between the block 15 and its veneer ply 13 over the veneer ply 14 and the outer veneer plies 11. This end cut, as indicated, must 30 be so proportioned that this travel will cause the end of the block 15 to come into abutment with the opposing stationary end that is securely glued in position. Prior to bending, the central block 15 is lifted as indicated by the dash lines, and a 35 film of glue is placed thereunder. Also glue is placed in the various slots and across the faces of the end cut. Following the bending of the panel, the bend is held in any suitable manner until this glue sets or dries so that the bend will 40 become permanent through the holding action of the glue.

It is to be noted that the veneer ply 14 which is glued to the block 15 securely ties together the individual blocks formed by the slots 17. Also 45 it is to be noted that by placing the inner plies of veneer 16 to have their grain extend transversely across the panel, the veneer remaining on the inside surfaces of the individual blocks between the slots will not tend to chip off while these slots are 50 being cut nor will they tend to separate thereafter.

As a modified form, it is possible, as indicated in Fig. 5, to form the core 15 without gluing its back to the under veneer 14, the initially loose 55

ply 14 being omitted in this form, and two plies 13 being used and glued to the outer plies 11. In this case, the block 15 is not cut entirely therethrough by the slots 17 so that the uncut portion 5 will serve as means to tie together the portions of the block between cuts.

In any event, the veneer plies 13 and 14 are preferably made out of relatively soft wood so that when the bend is formed, the portions of 10 the block 15 along the fold lines back of the slots 17 may embed themselves in these plies of soft wood instead of carrying those lines out in visible form through the outer plies 11. Of course, the closer the slots 17 are placed, the less 15 width there is between the slots around the bend adjacent the plies 13 and hence the less tendency there is for lines of folding of the block to show through the outer veneer plies when the bend is completed.

20 While I have herein shown my invention in the best form as now known to me, it is entirely obvious that structural changes may be made without departing from the spirit of the invention and I, therefore, do not desire to be limited 25 to that precise form beyond the limitations as may be imposed by the following claims.

I claim:

1. For a ply wood bend, a panel having a core, an outer veneer ply adhering thereto, an added 30 ply of veneer behind said outer ply extending at least over the zone of the bend, said core being provided with a plurality of relatively closely spaced slots extending transversely across the panel back of said added ply, that part of the 35 core which is cut being free to travel longitudinally of the panel relative to said outer ply and having an end portion removed equal to said travel.

2. For a ply wood bend, a panel having a core, 40 an outer veneer ply adhering thereto, an added ply of veneer behind said outer ply extending at least over the zone of the bend, said core being provided with a plurality of relatively closely spaced slots extending transversely across the 45 panel back of said added ply, that part of the core which is cut being free to travel longitudinally of the panel relative to said outer ply and having an end portion removed equal to said travel, said added ply being sufficiently soft to permit embedding therein of bends of said cut portion of the core occurring under said slots.

3. For a ply wood bend, a panel having a core, an outer veneer ply adhering thereto, a second 5 ply of veneer behind said outer ply extending at least over the zone of the bend, said core being provided with a plurality of relatively closely spaced slots extending transversely across the panel back of said second ply, that part of the core which is cut being free to travel longitudinally of the panel relative to said outer ply and having an end portion removed equal to said 10 travel, said slotted core portion having its back glued to said second veneer ply, and said second ply being anchored at one end and free to shift over the outer ply with said core portion.

4. For a ply wood bend, a panel having a core, 15 an outer veneer ply adhering thereto, a second 20 ply of veneer behind said outer ply extending at least over the zone of the bend, said core being provided with a plurality of relatively closely spaced slots extending transversely across the panel back of said second ply, that part of the core which is cut being free to travel longitudinally of the panel relative to said outer ply and having an end portion removed equal to said 25 travel, said slotted core portion having its back glued to said second veneer ply, and said second 30 ply being anchored at one end and free to shift over the outer ply with said core portion, said slots extending entirely through said core portion to said second ply.

5. For a ply wood bend, a panel having a core, an outer veneer ply adhering thereto, a second 35 ply of veneer behind said outer ply extending at least over the zone of the bend, said core being provided with a plurality of relatively closely spaced slots extending transversely across the panel back of said second ply, that part of the core which is cut being free to travel longitudinally of the panel relative to said outer ply and having an end portion removed equal to said 40 travel, said slotted core portion having its back glued to said second veneer ply, and said second 45 ply being anchored at one end and free to shift over the outer ply with said core portion, said slots extending entirely through said core portion to said second ply, that part of the core carrying said slots consisting of a separate filler block.

ELMO E. ALEXANDER.
